SMOKE ALARM HOUSING

Randolph J. Smith, Anaheim, Calif., assignor to Interstate Engineering Corporation, Anaheim, Calif., a corporation of California

Filed Oct. 21, 1965, Ser. No. 87,690

Term of patent 14 years

(Cl. D72—1)

FIG. 1.

FIG. 2.

FIG. 1 is a perspective view of a smoke alarm housing showing my new design; and

FIG. 2 is a side elevational view thereof.

The dominant features of my design reside in the portions shown in full lines.

I claim:

The ornamental design for a smoke alarm housing, as shown and described.
